UNITED STATES PATENT OFFICE

108,520

DESIGN FOR A CAPE

Max Teller, New York, N. Y.

Application January 4, 1938, Serial No. 74,081

Term of patent 3½ years

To all whom it may concern:

Be it known that I, Max Teller, a citizen of the United States and residing in Manhattan, in the city, county, and State of New York, have invented a new, original, and ornamental Design for a Cape, of which the following is a specification, reference being had to the accompanying drawing, forming part thereof.

Fig. 1 is a front view of a cape showing my new design.

Fig. 2 is a rear view thereof.

Fig. 3 is a view of Fig. 1 with the legs snapped in back instead of hanging loose.

The cape is composed of fox tails running diagonally from the rump of the animal in back over the shoulders.

I claim:

The ornamental design for a cape, substantially as shown and described.

MAX TELLER.
